UNITED STATES PATENT OFFICE.

CHARLES POTTER, OF PLAINFIELD, NEW JERSEY, ASSIGNOR TO THE POTTER PRINTING PRESS COMPANY, OF SAME PLACE.

CYLINDER PRINTING-MACHINE.

SPECIFICATION forming part of Letters Patent No. 628,490, dated July 11, 1899.

Application filed January 28, 1897. Serial No. 621,125. (No model.)

To all whom it may concern:

Be it known that I, CHARLES POTTER, a citizen of the United States of America, residing at Plainfield, Union county, State of New Jersey, have invented certain new and useful Improvements in Cylinder Printing-Machines, of which the following is a specification.

The present invention relates generally to bed and cylinder printing-machines, and more particularly to that class of such machines wherein the impression-cylinder is raised and lowered with respect to the form-bed. In such cylinder printing-machines it is desirable that some means be provided by which the wear in the cylinder-bearings may be compensated for, so that the impression shall at all times be uniform; and to this end the present improvements embrace a novel construction by which the position of the impression-cylinder with respect to the form-bed during the time of the impression is fixed and accurately determined independent of the cylinder-raising and lowering devices and of the form-bed.

The improved means consist of a cylinder raising and lowering device and an abutment forming a stop, or having the function of a stop, mounted on the frame of the machine and against which some portion of the cylinder abuts when the impression-cylinder is in its impression position, such abutment or stop being adjustable in height with respect to the axis of the cylinder, so that any wear in the parts may be compensated for and the impression position of the cylinder be preserved.

With this general understanding of the invention a detailed description thereof will now be given, reference being had to the accompanying drawings, in which—

Figure 1 is a sectional elevation of so much of a cylinder printing-machine as is necessary to an understanding of the invention, parts being broken away and those shown crowded together for lack of sufficient room to show them in their proper position. Fig. 2 is a transverse section of the same. Figs. 3 and 4 are modified forms of the abutment or stop.

The impression-cylinder C may be of any usual construction, co-operating with the usual form-bed B. The cylinder is carried by a shaft C', the journal of which is mounted in

bearings u, supported by the machine-framework A, the cylinder being driven from any suitable source of power—as, for instance, by power applied to the gear-wheel H, fast to the cylinder-shaft. For registering or other purposes the cylinder may carry a gear a, adapted to mesh with a tooth-rack b, fast to the side of the form-bed B. The location of the impression-cylinder with respect to the form-bed when in impression position is defined by an abutment or stop E, carried by the framework A in position to be borne against by some part of the cylinder C—as, for instance, its hub C². In the form of abutment shown in Figs. 1 and 2 it consists of a disk or wheel fixed or loosely rotatable on a stud e, projecting from a support or carrier e' and set eccentrically with respect to the axis thereof, so that by rotating the support to a more or less extent the upper surface of the disk or wheel will be raised or lowered, as the case may be. The support is mounted in bearings in the framework A and at its outer end carries an adjusting-plate e², having one or more slots e³, with which engage bolts e⁴, tapped into the framework, by means of which the plate, support, and disk may be firmly secured in any adjusted position.

The raising and lowering device for the cylinder may obviously partake of any suitable form, according to the desires of the maker, without in any manner affecting the scope of the present improvements. As an illustration of one form of such device the journal of the cylinder-shaft C' is surrounded by an eccentric sleeve interposed between said journal and its bearings u and adapted to be rotated more or less in said bearings to raise and lower the shaft and cylinder. This is effected automatically by a suitably-shaped cam O, mounted on and rotating with one of the driven shafts G of the machine, which cam is engaged at diametrically opposite points by antifriction-rolls p, carried by a yoked arm P', that is connected to a lever projecting from a rock-shaft P. This rock-shaft in turn carries another lever q', whose outer end engages the lower end of a rod s, the upper end of which is connected to an arm extending from the eccentric sleeve t'. When the uppermost antifriction-roll p moves from the

low part of the cam O, the rod s is moved vertically upward to partially rotate the sleeve, and thus raise the impression-cylinder from the plane of impression and from abutting 5 against the abutment or stop E, and when said antifriction-roll moves from the high part of the cam to its low part the impression-cylinder is lowered against the abutment and into the plane of impression. In practice the 10 eccentric sleeve will be such as to allow the cylinder to reach the lowest desired position, so that as the parts wear and the abutment E is adjusted to offset such wear and determine the exact impression position of the cylinder there need be no change in the extent 15 of movement imparted by the cam to the connections between it and the eccentric sleeve.

In the raising and lowering device shown there is a slip connection provided between 20 the lever q' and the rod s, so that the cylinder may be left in its raised position for any desired period of time. Thus normally the stud q^2 of the lever q' rests in an offset at the upper end of a curved slot s, such position being maintained by a spring x, interposed between the rod and a projection from the lever q' . When the connection between the lever and rod is desired, the pressman by 25 any suitable means simply rocks an arm v over against the rod and moves it to the left against the force of the spring, so that the slot is brought into alignment with the stud q^2 , whereupon the lever may make any number of idle movements with its stud playing 30 loosely in said slot, leaving the cylinder in its raised position. By causing the arm to be rocked in the reverse directions the spring x restores the rod to its normal position, so that the stud will again engage with the off- 35 set of the slotted end of the rod.

It should be understood that no claim is herein made to the cylinder raising and lowering device shown and described, as such device forms the subject of an application 45 filed by me on or about April 11, 1896, Serial No. 587,117.

It is obvious that other forms of the abutment or stop E may be adopted without materially affecting the scope of this invention. 50 Thus in the modified form shown in Fig. 3 the abutment is provided with a curved seat e^5 , in which the cylinder-shaft or the cylinder-hub C² may rest when the cylinder is in its down or impression position. Such an abutment is 55 carried loosely on the inner end of a stud, as in Fig. 1, set eccentric to the rotatably-ad-

justable carrier of said figure, the abutment being prevented from turning and becoming displaced by its upper ends meeting the cylinder-hub, the cylinder never being raised 60 sufficiently for said ends to escape meeting the hub.

In the modification shown in Fig. 4 the abutment E is in the form of an eccentric e⁶, fixed to the inner end of the rotatably-adjustable 65 carrier e' and adjusted bodily with the carrier when it is moved for that purpose.

When only one abutment E at one side of the impression-cylinder has been specifically referred to, it will be understood that it will 70 be duplicated upon the other side, so that the position of the cylinder with respect to the form-bed may be accurately fixed at both of its ends.

What I claim is—

1. The combination with an impression-cylinder, its coacting form-bed and the cylinder raising and lowering device, of an abutment independent of the cylinder and its bed in position upon the final movement of the lowering device to bring and hold the top portion 80 of the cylinder-bearings firmly against the upper portions of the journals during the impression movements, as described.

2. The combination with an impression-cylinder, its coacting form-bed, and the cylinder lowering and raising device, of an abutment mounted independent of the cylinder and its bed in position upon the final movement of the lowering device to bring and hold the top 90 portion of the cylinder-bearings firmly against the upper portions of the journals during the impression movements and means for adjusting the position of the abutment, as set forth.

3. The combination with an impression-cylinder, its coacting form-bed and the cylinder raising and lowering device, of an abutment consisting of a support or carrier rotatably mounted in the framework at each end of the cylinder and carrying a disk or the like against 95 which the adjacent portion of the cylinder may rest when in its impression position and adapted to determine the position of the cylinder upon the return of the said raising and lowering devices, as set forth.

In witness whereof I have hereunto set my hand in the presence of two witnesses.

CHARLES POTTER.
